WINDOW SCREEN

Seth J. Gilson, Cleveland, Ohio, assignor to Gilson & Neeb Company, Cleveland, Ohio, a partnership

Application April 24, 1945, Serial No. 590,022

8 Claims. (Cl. 160—374)

1

The object of my present invention has been to produce a novel form of adjustable window screen.

A primary feature of my invention resides in the special construction of frame for the screen whereby I am enabled to employ a screen member or screen members of fixed width notwithstanding that my screen is adjustable to occupy windows of different widths in order that it may fit the particular window upon which it will be finally disposed for use. The reason that I am enabled to utilize screen members of uniform or predetermined width is due to the fact that in the construction of my screen unit I avail of adjustment of relatively wide side frame members in order to obtain the variable widths for my screen that will permit of its application or fitting to different widths of windows. The side frame members are assembled in a somewhat unique manner in relation to the screen member or members, whereby to be adjusted in respect to the latter, the side edges of the screen members fitting into the side frame members of my unit, which frame members may slide relatively to the screen members for adjustment facility.

My screen unit is also novel in respect to the provision of plural screen members if the latter are to be used, there being provided a special arrangement of such screen members disposed in vertical line with one another and adapted to overlap to provide the necessary continuous screen surface for my screen, suitable means being supplied for obtaining the necessary guiding functions of the screen members on the frame and relatively to each other when moving the same to predetermined adjustments depending on the vertical height of a particular window to which the screen is to be fitted.

My invention involves other special features of construction designed for facilitating the assembly and adjustment of the parts or members of a screen of the type which I have devised, and which features will be fully understood upon reference to the following specification, in conjunction with the accompanying drawings, in which:

Figure 1 is a view of my screen invention mounted on a window and looking at the screen from the outside of the window.

Figure 2 is a view of the screen alone, looking toward the same from the inner side thereof.

Figure 3 is a view similar to Figure 2, but illustrating the screen as seen when adjusted to enlarge the width thereof and to extend the screen longitudinally or vertically.

2

Figure 4 is a vertical sectional view of the screen alone taken about on the line 4—4 of Figures 1 and 2.

Figure 5 is a vertical sectional view of the assembled screen taken about on the line 5—5 of Figure 2.

Figure 6 is a horizontal sectional view taken about on the line 6—6 of Figure 2.

Figure 7 is a horizontal sectional view taken about on the line 7—7 of Figure 2.

Figure 8 is a view illustrating the screen members as when separated from the extensible frame members.

Figure 9 is a view in elevation of the lower screen member alone.

Figure 10 is a view of one of the side frame members alone, looking in the direction of the outer side edge of the screen.

Figure 11 is a detail perspective view of one of 20 the guide plates attached to the lower end of the upper extensible section of each side frame member.

Figure 12 is a detail sectional view on the line 12—12 of Figures 3 and 8.

Figure 13 is a cross sectional view of the lower section of each side frame member.

Figure 14 is an edge view of one of the side frame members, looking toward the outer edge portion thereof.

Figure 15 is a perspective view of one of the U-shaped stops at the upper end of each lower side frame member.

Figure 16 is a perspective view of the stop member on each end of the upper cross bar of 35 the lower screen member.

Specifically describing my screen construction, and referring to the drawings, it is noted that my screen comprises a lower screen member seen best in Figures 8 and 9, said member comprising the screen body or material 1, at the side edges of which are attached by rivets or otherwise the metal strips 2, the said strips 2 supporting at their upper ends the cross bar or strip 3 which reinforces the upper edge of the screen member or material 1 and is also attached to the latter at said upper edge. The lower end of the screen member 1 has affixed thereto a cross or bottom frame member 4, which is of fixed length slightly greater than the width of the screen member 1, and between the front and rear sides of which are received the lower ends of the metal strips 2. The bottom frame member 4 may be made in two sections so as to receive therebetween the metal strips 2 and the lower end portion of the 55 screen member or material 1, the outer section

of the frame member 4 thus referred to being relatively thin and being designated 4a. Carried by the lower frame member 4 are the U-shaped guide members 5. The section 4a of the member 4 extends a short distance above the upper edge of the inner body section of the said frame member, as seen best in Figure 12.

The foregoing sets forth the general construction of the main or lower screen member of my screen.

The upper screen member of my screen is designated 6 and is made of the usual screen material carried primarily by the upper cross frame member 7 of my screen, which frame member is seen best in Figure 8 as comprising a relatively heavy and vertically wide dimensioned cross bar made up of a relatively thick outer section and a relatively thin inner section of material such as wood or other substance from which the screen frame structures may be made. The upper edge of the screen member or material 6 is received between the two sections of the member 7, as seen best in sectional view Figure 13, and attached to the outer section of the member 7 and extending downwardly therefrom are flanged side bars of metal designated 9, the same being connected at their lower ends by the cross bar 10 secured at its opposite ends to the metal bars 9, which latter are formed with gusset sections 9a at their lower ends to reinforce the connection between the parts 9 and 10. Attached to the inner faces of the flanged metal bars are strips 9b of wood or suitable material, between which and the bars 9 the vertical edges of the screen member or material 6 are clamped and fastened by suitable fastening brads or like fastenings passing through the parts 6, 9, and 9b.

The upper screen member thus described and comprising largely the parts 7, 9, 10, and 9b affords a relatively rigid frame member structure.

In the operative assembly of the screen with the upper and lower screen members together as seen in Figure 4, the lower cross bar 10 of the upper screen member, which is grooved in its upper edge to receive the edge portion of the screen member or material 6, is adapted to abut at its outer upper edge with the inner lower edge of the cross bar 3 of the outer screen member 1 and limit the upward extending action of the screen members 1 and 6 by such abutment action.

I pass now to the construction of the side frame members of my screen, both of which side frame members are made exactly the same so that they are practically interchangeable in the assembly of the screen. I shall describe, in conjunction with the disclosure of Figure 10 of my drawings, the structure of each of these side frame members as follows. Each side frame member is generally designated 1a and is made up of an upper section 11 and a lower section 12. The upper section 11 is composed of inner and outer members spaced from each other so as to receive therebetween the portion 12a of the lower section 12. Now this lower section 12 is made up of the vertically extending main and longer portion 12a, previously mentioned, the same having a vertical groove 13 leading from its inner edge outwardly to receive the adjacent vertical side metal strip or part 2 of the screen member 1. The groove 13 of each side frame section 12 is a deep groove and not only receives the adjacent metal plate or strip 2 of the screen member 1, but permits this reinforcing metal member 2 and the adjacent screen material to move laterally in such groove so as to enable each side

frame member A to be shifted horizontally or laterally respecting the screen member 1 to a limit of movement controlled by the length of slots 15 provided in the upper cross frame member 7 and the lower cross frame member 4 of the two screen members 6 and 1, respectively.

Said lower section 12 of each frame member is provided with spaced lower corner plates or members 16 which are attached at their upper portions to opposite sides of the part 12a, and the lower portions 16a are sufficiently spaced, in respect to the complementary side frame members A, to receive therebetween the opposite ends of the bottom frame member 4, the parts 16a being adapted to slide horizontally or relatively to the member 4 in the lateral extension or contraction of the screen unit by means of adjustment of the members A from and toward each other, respectively. For facilitating the proper relative horizontal movement between the parts 4 and 16a of the side frame members A, I utilize a guide member 17 which projects inwardly from each member 16a and slides on top of the inner section of the bottom cross frame member 4. Each guide member 17 is adapted to operate in one of the keepers or guide members 5, previously referred to, as carried by the bottom frame member 4.

In reference to the upper section 11 of each of the side frame members A, the upper frame member 11 receives between its spaced parts the portion 12a of the lower section of the frame member A, as previously described, and it is notable that at the lower portion of the section 11 I provide a guide strip or member 18 made preferably of metal, and which, at the outer edge of the side frame member A, spans the space between the parts of which the member 11 is composed, crossing such space at the outer lower edge portion of the member 11, as seen at 18a. The guide strips 18 hold the parts 12a of the side frame members A in proper sliding alignment with the upper sections 11 of the members A adjacent to the lower portions of said sections 11.

At the inner edge of each section 11 there is provided a strip of material in the nature of a guiding and stop strip 19 which works in sliding abutment with the adjacent inner edge of the part 12a of the lower section 12 coating thus with the strip 18 to keep the parts 12a and 11 in vertical alignment. The section 11 of each side frame is virtually made of inner and outer flat members of wood or similar material connected together at their upper outer edges by a strip of material 20 similar to that designated 19, and which acts in cooperation with the part 19 to hold the sections 11 and 12 in alining positions freely permitting the vertical sliding movements of these sections for the purpose of vertical extension and contraction of the screen members 6 and 1. At the upper end of the section 11 of each side frame member A the spaced parts of said member are extended inwardly to provide spaced lateral extensions 21, on the inner side of one of which is attached a guide member 22 somewhat similar to the guide member 17 previously described in reference to the lower section 12. This guide member 22 is adapted to slide in abutment with the under side of the upper cross bar 7 of the upper screen member 6 and the latter may be equipped with keepers 23 to coact with the guide members 22 of the side frame members A after the same manner of cooperation as the guide members or keepers 5 coact with the lower guide members 17. See Fig-

ure 8 for the details of construction above referred to in relation to their separated position, and Figures 1 and 2 in relation to the arrangement of these guide parts in their assembled position when the screen is in the form of an operative unit.

For connecting the side frame members A with the screen members 1 and 6, I utilize screw bolts passing through openings 24 in the parts 21 and 15a, said screw bolts designated 25, and also passing through the slots 15 of the parts 7 and 4, as previously described. These screw bolts 25 cooperate with the slots 15 to limit the lateral or widening extension of the screen and the narrowing contraction of the screen in the direction of its width.

For additionally assisting in holding the main screen member 1 with its vertical edges and parts, in the grooves 13, the upper ends of the lower side frame sections 12 have at their upper ends U-shaped corner stop members 26 which have cross webs 26a that constitute stops. Said stops 26a are engageable with stop lugs 27 which are directly attached to opposite extremities of the part 3. The loops 26a can slide against the lugs 27 as seen according to the disclosure in Figures 15, 16, and 18, and thus limit the outward movement of the parts 12a at the upper ends of the latter.

For supporting the screen upon a window in which it will be emplaced, I utilize a supporting plate 28 attached to the outer side of the cross bar 7 after known practice, said plate having a slot to engage with a lug carried by a plate 29 attached to the upper cross bar B of the frame of the window which is indicated at C generally.

For quick loosening of the fastening bolts 25, wing nuts 30 are applied to said bolts at the inner side of the screen. For interlocking the screen at its lower end to the window frame, the members 15a are equipped, as seen in Figure 3, with L-shaped clip members 31 adapted to interengage with the outer window sash stop strips of the window frame.

The method of mounting and the operation of my window screen, according to the structure before described, is as follows: It is assumed that the screen members are assembled substantially in the condition in which they are seen in Figure 2. The screen will have the wing nuts 30 loosened preliminary to placing the screen in the window frame, and this will permit of ready separating or moving together of the side frame members A, and since the upper sections 11 of said side frame members are loosely slideable in relation to the lower sections 12, the vertical extension of the screen may be readily effected, dependent upon the vertical dimension of the window frame.

The parts being so set and arranged, say as seen in Figure 2, the first step is to pass the window screen through the window from the inside and interengage the plates 28 and 29 after the known manner of suspending and supporting screens as practiced today. The operator will spread the side frame members A if the window is wider than the adjustment of the parts as seen in Figure 2, the latter adjustment being the minimum width to which the screen parts can be set. This separation will cause the screen members and frame parts to properly engage the sides of the window frame and the vertical dimension of the screen will be arrived at by merely permitting the lower sections of the side frame members A to gravitate relatively

to the upper sections 11 until the lower frame bar 4 rests upon the usually outwardly inclined sill of the window frame. Then the clips or fastening members 31 can be interengaged with the lower ends of the outermost stop strips of the frame. With such adjustment of the parts, the thumb nuts 30 will be screwed up tight to hold the frame members in their proper positions. Of course, if desired, a suitable fastening device can be employed to attach the lower frame bar 4 to the window frame, but this is not necessary. The cross bar or strip 10 of the upper screen member 6 and the cross bar or strip 3 of the lower screen member 1 contact each with the screen material of the opposing screen member and seal the space between the screen members at whatever vertical adjustments they assume, preventing entrance of dirt and also insects at such point of contact.

It will thus be seen that I have devised a screen which is adjustable in width to an extent substantially equal to the width of the frame members A, and is further adjustable in length a distance equivalent to the combined lengths of the screen members 1 and 6. At all lateral adjustments of the members A the vertical edges of the screen members 1 and 6 remain housed or inset within the members A.

It is to be comprehended within the scope of my invention that screens of fixed vertical length may be produced using the general principle of construction employed by me and utilizing only the main screen member 1. Under such conditions the secondary screen member 6 could be dispensed with.

Having thus described my invention, what I claim as new and desire to secure by Letters Patent of the United States, is—

1. A window screen comprising, in combination, side frame members, a main screen member therebetween, the side edge portions of which overlap the side members and are movable laterally relatively thereto, and upper and lower frame members adjustably connected to the side frame members, said side frame members being longitudinally extensible relatively to each other.

2. A window screen comprising, in combination, side frame members, a main screen member therebetween, the side edge portions of which overlap the side frame members and are movable relatively thereto, upper and lower frame members, and adjustable connecting means between the side frame members and said upper and lower members limiting the movement of the side frame members in opposite directions, and preventing the separation of the screen member and said side frame members by movement of the latter away from each other.

3. A screen as claimed in claim 1, combined with horizontal guide members extending inward from the side frame members and cooperating with the upper and lower frame members to direct the movement of the side frame members when shifted toward or from each other in adjusting the parts to vary the width of the screen.

4. A window screen as claimed in claim 1, wherein the side frame members are formed with grooves extending outward from their inner edges, in which grooves the side edge portions of the screen member are received and adapted to shift upon adjustment of the side frame members toward or from each other to vary the width of the screen and primary guide members extending inward from the upper and lower ends of the side frame members and slidably

engaging the upper and lower frame members, and secondary guide members on the upper and lower frame members to engage the primary guide members and coacting to prevent planar separation of the frame members.

5. A screen as claimed in claim 1, combined with a second screen member adjustable vertically relatively to the main screen member, and in which the side frame members are composed of relatively vertically movable sections facilitating movement of the second screen member in relation to the main screen member, the main screen member having its side edges received by the lower of the adjustable sections of the side frame members, and the second screen member having its side edges correspondingly received by the upper of said adjustable sections.

6. A screen as claimed in claim 1, combined with a second screen member adjustable vertically relatively to the main screen member, and in which the side frame members are composed of relatively vertically movable sections facilitating movement of the second screen member in relation to the main screen member, the second screen member being movable above the main screen member, and cross bars at the lower end of the second screen member and the upper end of the main screen member, each cross bar operating in contact with the screen material of the screen member having the other cross bar and sealing the space between the screen members.

7. A window screen comprising upper and lower screen members, connected side frame members receiving the side edges of the said screen members, said edges movably overlapping considerable portions of the width of the side frame members for varying width adjustments, said side frame members being vertically adjustable to facilitate vertical relative adjustment of the upper and lower screen members.

10 8. A screen as claimed in claim 7, in which the screen members and side frame members are relatively movable for varying the width of the screen, combined with manipulatable fastenings between the side frame members and the upper and lower screen members operable to fix the width adjustments obtained by relative movement of the screen members and side frame members in the direction of the width of the screen.
